[57] **CLAIM**

The ornamental design for a housing for a personal transmitter for use in an emergency alarm system, as shown and described.

DESCRIPTION

FIG. 1 is a top perspective view of a housing for a personal transmitter for use in an emergency alarm system showing my new design;

FIG. 2 is a bottom perspective view thereof;

FIG. 3 is an exploded front elevational view thereof;
FIG. 4 is a side elevational view taken from the right of FIG. 3;

FIG. 5 is a side elevational view taken from the left of FIG. 3; the inner housing shown separately from the cover for clarity of illustration;

FIG. 6 is a bottom plan view taken in the direction of the arrows along lines 6—6 of FIG. 5;

FIG. 7 is a top plan view taken in the direction of the arrows along line 7—7 of FIG. 5;

FIG. 8 is a top plan view of the outer cover portion taken in the direction of the arrows along line 8—8 of FIG. 3.

FIG. 1

FIG. 2

FIG. 5

FIG. 3

FIG. 4

FIG. 6

FIG. 7

FIG. 8
